[57] CLAIM

The ornamental design for a combined display and self-service merchandising cabinet, as shown and described.

DESCRIPTION

FIG. 1 is a front elevational view of a combined display and self-service merchandising cabinet showing my new design;

FIG. 2 is a top plan view thereof;

FIG. 3 is a right side view thereof, the side opposite being a mirror image;

FIG. 4 is a rear elevational view thereof; and,

FIG. 5 is a perspective view thereof with one of the hinged bin lids in open condition and one of the serving scoops in an alternate position for use.

The broken line showing in FIG. 5 is for illustrative purposes only.
